FRED J. SERSEN, OF BROOKLYN, NEW YORK, ASSIGNOR OF ONE-HALF TO JOHN H. THOMAS, OF NEW YORK, N. Y.

STUD AND PARTITION CONSTRUCTION FOR BUILDINGS

Application filed September 21, 1929. Serial No. 394,214.

My present invention refers to stud and partition construction for buildings of various kinds, more especially office buildings, hotels, and other large structures in cities.

5 Among many advantages and objects that might be enumerated, I mention sound-deadening; ease, facility and speed in erection; cheapness of material and arrangement of details; strength and rigidity; and more especially the sound-proof, simple and efficient character of the partition construction, including a novel and rigid stud, together with novel air-spatial plans; all combined to promote economy without the sacrifice of architectural advantages.

With these leading objects in view, and others that will appear as I proceed to discuss the details and their relation and use, it may be said in general that the invention 20 consists in the construction, combination, and arrangement of parts, and numerous peculiarities thereof, substantially as will be hereinafter described and claimed.

In the accompanying drawings illustrating 25 my invention:

Figure 1 is a horizontal section of a selected portion of my improved building construction, showing the relation that the various parts sustain to each other in a partition wall.

Figure 2 is a vertical section of the complete partition on the line 2, 2, of Figure 1.

Figure 3 is a perspective view of one of the studs.

35 Figure 4 is a horizontal sectional plan of the stud on the line 4, 4, of Figure 2.

Figure 5 is a segment of the partition wall, indicating more or less in conventional outline the main features of such wall.

40 Similar characters of reference denote like parts throughout all the different figures of the drawings.

A leading feature is the stud or upright post A, which is formed of steel or other metal 45 in a right-angled channel or similar angular form like a horizontal U or L. Stud A has therefore the three sides 1, 2, and 3, which may be about the same in width. One of these sides or webs, as 1, is rebent on itself as 4, and 50 extended beyond the intermediate side 2 to

provide a projecting member 6; the members 6 and 4 lying in the same plane and constituting an integral member double the width of either of the single parts 1, 2, or 3, so that these two parts 3 and 4, 6, are parallel to each other, and part 4, 6, is twice as wide as the other part 3, so that on one side the stud presents a face much wider than it does on the other side. This helps in holding the wall board against the opposite side of the stud. 55 The side 6 at intervals has integral lugs 5 cut out of the same and turned at a right angle to the face of side 4. See Figure 2. These lugs 5 have each a pair of perforations a and b, for a purpose that will appear. Lugs 5 lie in the same plane as intermediate side 2, because they are turned out at a right angle at the point where the rebent side 4 merges 60 into the projecting side 6, the sides 4 and 6 being integral with each other as stated. 65

Although I describe the entire channelled stud as made in a single piece, yet it is quite obvious that it may be made in several parts secured together. Thus the U-shaped part 75 might be one piece, and the combined side 4 and 6 might be another plate secured to a side of the U-shaped member, but providing the perforated lugs as before.

Taking this unique and novel stud feature 80 as the main factor in the partition construction, I proceed to describe how it is utilized in building up a sound-proof wall, as shown in detail in Figures 1 and 2. There is a plurality of these studs erected between sections 85 of wall board, the outer sides of which are overlaid with plaster and metal lath, while between these sections are one or more dead air spaces 21 and 22, as narrow or as wide as experiment may suggest to be useful and 90 adequate.

In the main frame of a building the ceiling of one story will have angle beams C or some equivalent members with which the upper end of each stud may be connected, said beam C having a horizontal leg or web c1 and a vertical leg c2, both of which may have the usual bolt or rivet holes. Also the flooring will have similar L beams D or equivalent pieces to which the lower ends of the studs 95 may be secured, these L beams having hori-

zontal legs or webs d and vertical legs d_1 provided with the usual bolt or rivet holes. The studs when placed vertically will reach from floor to ceiling, but as ceiling heights vary in 5 different structures it is necessary to have an extension member on one end of each stud which can be adjusted more or less to make the stud longer or shorter. This adjustable part I usually place at the top, and it consists 10 of a channel iron B having three sides like the three sides of the stud member A, said channel member B being slightly smaller than A so that it will fit inside of A. See Figures 2 and 4.

15 The extension member B is secured within stud portion A by a bolt or other device 20 which passes through a slot 19 in the intermediate part of channel piece B and a coinciding slot in stud A, the slots being long enough to permit of considerable adjustment 20 so that the entire stud may be caused to have just the right length to reach from the floor to the ceiling, and when so placed the nut on bolt 20 can be tightened and the parts held 25 together. The upper end of top member B has a perforated lug 23 similar to and aligned with lugs 5 all serving the same purpose; and top B is placed snugly within the angle of beam C and securely bolted or fastened. 30 Likewise the lower end of the stud is bolted or fastened to the L beam D, whose sides d and d_1 have as many bolt holes as may be needed to bolt it in place. In assembling the 35 partition details therefore I first erect a suitable number of studs say one series, and after they are secure place against and with them the wall boards.

So far as the board features are concerned, I reserve the right to use boards of any desired material, natural or artificial; either wood, or metal, or a fibrous substance, or a combination of them, or a manufactured or natural composite substance; usually rather thin and light, and in prepared sheets or sections suitable for the purpose.

When a few studs are erected at suitable intervals apart, as shown in the top row of studs in Figure 1, with the lugs 5 projecting in the same direction outwardly, the outer 50 wall boards 13 and 14 will be placed in a line with their vertical edges in contact with the lugs 5. The contact may be tight, or loose and easy as preferred. The board 13 rests against one side of the lugs 5 and also against 55 the adjacent face of the stud; while on the opposite side of the lugs 5 the edges of other boards 14 are placed, whose sides are also against the adjacent faces of the studs.

Then through the perforations a in the 60 lugs 5 are driven the wedges 7 on the outer side of the boards 13 and 14, so that the boards are closely fastened to the studs and in line with each other. After these parts are thus placed the plaster coat 9 is applied 65 to boards 13 and 14 in connection with the

metal lathing 10 which supports the plaster. The lathing 10 is fastened across and to the lugs 5 by pieces of wire 8 wound through the meshes of the lath and the perforations b of the lugs 5 and the end of the wire tightly twisted together. 70

On the side of the boards 13 and 14 opposite to the plastered coat 9 is an air space 21 equal in size to the width of the channel beams A that form part of the studs. Next I support board 15 on the other side of these studs against the legs or webs 3 of the channel pieces A, and against board 15. I also employ a series of flat boards 16 so that two thicknesses of boards are used here, their ends overlapping, but preferably the two thicknesses are not continuously so, but their ends overlap to allow at least a single unbroken thickness the whole length of the partition, and the overlapping is opposite to the studs. Boards 15 and 16 form the other side of an air space 21. 80

90 The construction I have just described for one row of studs is duplicated with another row of studs to make the full thickness of the partition with another air space at 22 on the side of the middle line of boards 15 and 16 opposite to the air space 21. This is shown fully in Figure 1. The exception on this side in the arrangement of the parts is that the studs are reversely placed, that is the channels A therein open in a direction opposite to the direction of the opening in the channels in the first row, and the lugs 5 project the other way. 95

100 This arrangement however is merely a preferred detail of location for the studs and in order to produce a more balanced assembly, and I am by no means confined thereto but may vary it as much as I please. The boards 16 are closely against the second row of studs. On the other side of the studs are the boards 17 and 18 arranged in a manner similar to the boards 13 and 14 and locked by wedges 7 to the studs. The outside 110 surface of boards 17 and 18 is covered with a plaster coat at 11 with metal lath 12, the latter held by the wires 8 in the perforated lugs 5. 115

120 While my improved partition construction is more effectually sound-proofed by a complete construction as I have just described where double air spaces are employed, yet an efficient result is attained by the use of one air space and my invention is broad enough to cover a single air chamber and a wall with half the features that are duplicated in the foregoing recital. Further, it will be understood that the details 125 may be changed in many ways without exceeding the scope of the claims; and I therefore reserve the liberty of modifying, adding to and taking from the mechanical features in order to suit the invention for use wher- 130

ever it is adapted to be specialized for the needs of individual cases.

What I claim is:

1. In building construction, a stud having a right-angled channel formed by two parallel webs and an integral intermediate member, another member alongside one of said webs and widened to form a surface substantially larger than said web, the outer edge thereof being incut at intervals and the sections between the cuts being bent at an angle to form lugs in the same plane with the intermediate member of the channel, said lugs being perforated, and fastening means for wall boards being passed through one perforation, and fastening means for lathing being passed through another perforation, so that the lugs and fastening may hold the constituents of the wall close against the studs.
2. In building construction, a stud having a channel formed by two parallel webs and an integral slotted intermediate member, one of said webs being rebent on itself and widened to form a substantial wide surface, the material of the outer edges being cut at intervals and the sections between the cuts turned at an angle to form lugs that are provided with means for securing wall boards to the studs, said lugs being in the same plane with the intermediate member of the channel, in combination with a channeled and slotted extension member of smaller cross section than the stud that slides in the channel of the stud so as to adjust and regulate the length of the latter to the required distance between floors, said extension having a lug in the same plane as and cooperating with the other lugs, and bolting means passing through the coinciding slots to secure the extension piece to the main stud at the proper point.

In testimony whereof I hereunto affix my signature.

FRED J. SERSEN.
